ATTORNEY.

UNITED STATES PATENT OFFICE.

HARRY E. SOREF, OF MILWAUKEE, WISCONSIN.

LOCK.

Application filed May 10, 1926. Serial No. 108,039.

This invention relates to locks that include a chain, cable, or other flexible means, employed for surrounding articles to be securely fastened, such as, spare automobile 5 tires, the meeting bars of gates, or similarly disposed objects adapted for locking with a device of the kind here considered.

The objects of this invention, are: to provide a lock that remains part of a flexible 10 element which may be used as a binding tie; the providing of a loosely attached lock which is linked to permanently form part of the assembly that may comprise any flexible means having the faculties of a chain, rope, 15 or cable having a terminal loop opposite the lock proper that is enterable in the shackle of the lock along with the permanently attached terminal; the offering of a link element that is operably free in the shackle of 20 a lock whether same be open or closed and still remain connected thereto; and the providing of a swivel feature that may be turned for releasing the free-coupling opposite terminal of a flexible length upon 25 unlocking the shackle element of a lock body.

Other objects will be apparent in the specification, and pointed out in the claims which refer to the accompanying drawings that is comprised in this application.

Referring to the several views:—

Fig. 1 is a view showing the adaptation of this invention. Fig. 2 is an enlarged fragmentary view of the device. Fig. 3 is a view similar to Fig. 2, parts being broken 35 away and the locked relation shown dotted. Fig. 4 is a perspective view showing the opened shackle relation to the initial link member. Fig. 5 is a modified form of link member locked; the unlocked relationship 40 being indicated in dotted lines.

Similar characters of reference apply to like parts throughout the several views, the same illustrating one size or style which, it is here noted, may be varied in proportions, 45 or designs to suit a variety of tastes or requirements, without departing from the spirit of the invention here disclosed.

A particular embodiment shows, as in Fig. 1, a lock body L having a shackle S 50 connected to a chain C by an intermediate member M. The chain C may be passed around an object and its opposite terminal hooked into the shackle S, the said figure showing the device as applied for securing 55 an automobile tire to its carrier.

Figs. 2 and 3 show the locking end in detail which discloses the member M as comprising opposed plates P—P that are spaced apart by pivots p and p' which forms an integral unit offering a slot X between the 60 said plates wherein lie, in an unchanging plane with respect to each other, the shackle S and the first, or, initial link c of the chain length C; a plane that is common to the shackle S, the member M and the said first 65 link c. With an arrangement of this kind a length of structure equal to the several members thus connected, is offered for passing one end through an opening, thereby avoiding the soiling of clothing through 70 groping around the muddy wheel and frame elements of autos; or, when passing this shackle means through openings where a hand cannot enter. Another valuable feature gained by adopting the "figure 8" 75 design of intermediate link, is, the minimizing of space between said link and a shackle, through which prying tools may be inserted for forcing locks of the kind here employed. The lock L is of known design wherein the 80 shackle S, upon being unlocked, will reciprocate in the body of said lock and also swing about a hinged leg s to rotate the other leg s' clear of the said body portion, whereupon 85 the link c may be released from, or attached to the shackle S, as shown in Fig. 3.

Fig. 4 illustrates the permanent connection between the lock L and the member M while permitting rotation in one plane between the shackle S and the said member. 90 The shackle's U-shaped formation which surrounds the spacing pivot p , permits the said member to be swung about said pivot when the shackle is either locked or unlocked. However when the unlocked position of the 95 shackle is effected the shackle leg s' is clear of the lock sufficiently to allow of another freely pendant link being, either hooked to, or unhooked from the aforesaid shackle, but the space between the lock body and the leg s', with regard to the open position, is less than the diameter of the pivot p , thus preventing the member M from ever leaving the shackle and always providing a lock unit 100 at hand.

Fig. 5 is a modification which discloses an assembly similar in design and genus to what is described above, with the exception that a gap R is provided in the member M 105 to receive a link of a flexible member simi- 110

lar to link *c*. The gap *R* is made at a point on plates similar to *P*—*P* which gap passes through the circumference of the pivot *p*'' where same will not affect the pivot's diameter so as to allow passage of same through the space between the lock body and the leg *s*' as illustrated in Fig. 4; because, when the gap *R* is turned to release the confined link the pivot's diameter will still be greater than the space that is large enough to free the intended terminal of the flexible member.

It will be noticed that this device allows the dropping of one, or any number of links, and locking the chain along its length whenever choice or occasion may require, that is, the confined or locked portion is not restricted to a terminal element only.

Having described my invention what is desired to protect by United States Letters 20 Patent, is:—

1. In a securing means the combination of, an intermediate link connecting a chain member to a locking means, parallel and separated plates offering a slot in said link, 25 pivotal spacing studs separating the said plates and longitudinally limiting the slot aforesaid, a lock body provided with a **U**-shaped lock shackle permanently pivoted about one of said studs and an initial link 30 of said chain member similarly pivoted about the other stud.
2. In a securing means the combination of a lock member provided with a **U**-shaped shackle element, a flexible portion, a link 35 pivotally connecting together the said shackle and the portion aforesaid, a loop end on the flexible portion, pivotally attached to said link, a slot formation fashioned in the link aforesaid; said slot adapted to restrict 40 the said shackle, link, and loop end to be oscillatable in a common plane.

3. A securing means comprising a lock and shackle assembly; a flexible chain link portion; and an intermediate member formed of spaced plates; said member offering pivoting studs therein about which pivotally 45 swivel in like plane the shackle aforesaid, and an initial loop of the portion aforesaid; the lock and shackle assembly and its respective pivotal connection being relatively 50 proportioned to prevent separation of said assembly and said member when the said shackle is open.

4. A securing assembly comprising a flexible binding element having at one end a 55 reciprocal **U**-shaped shackle rotatively mounted in the lock and at the other end a series of chain links; one of said chain links adapted to be freely retained within the **U**-shaped shackle along with a permanently 60 joined, restrictedly movable unitary shackle connection; said connection being independent of the aforesaid lock.

5. A securing means having, an intermediate member for pivotally connecting a **U**-shaped shackle element of a lock body and the initial link of a chain series between its 65 sides, said member shaped to approximate the area inclosed by the said element less a space provided for admitting a selected link 70 of the chain series within the area aforesaid.

6. A securing means having a link member formed of flat parallel sides, said sides spaced by pivoting studs, a lock shackle permanently embracing one of said studs between the sides aforesaid, said sides finished to concentrically end about said studs on a radius slightly less than the outer radius of the aforesaid shackle.

In testimony of which, I hereby affix 80 my signature.

HARRY E. SOREF.
